IRONER

George W. Wardwell, Jr., Nichols, Conn., assignor
to General Electric Company, a corporation of
New York

Application October 4, 1938, Serial No. 233,253

3 Claims. (Cl. 38—60)

The present invention relates to rotary ironers of the type having cooperating ironing members comprising a roll and a shoe.

The object of my invention is to provide an improved construction and arrangement in rotary ironers, and for a consideration of what I believe to be novel and my invention, attention is directed to the following description and the claims appended thereto.

In the accompanying drawings, Fig. 1 is a perspective view of a rotary ironer embodying my invention; Fig. 2 is a sectional end elevation of the driving mechanism; Fig. 3 is a sectional view taken on line 3—3 of Fig. 2; Fig. 4 is a fragmentary view of the trip lever and the associated mechanism controlling the engagement and separation of the ironing members; Fig. 5 is a sectional front elevation of the ironer; Fig. 6 is a sectional view taken on line 6—6 of Fig. 5; Fig. 7 is a perspective view of the clutch member for moving the shoe toward and away from the roll; Fig. 8 is a perspective view of one of the clutch keys carried in the clutch member; Fig. 9 is an end elevation of the shoe and its associated parts, the shoe being shown separated from the roll; Fig. 10 is a view similar to Fig. 9, the shoe being shown against the roll; Fig. 11 is a sectional view taken on line 11—11 of Fig. 9; Fig. 12 is a sectional view taken on line 12—12 of Fig. 9; Fig. 13 is a perspective view of the hub connecting the shoe and the rock shaft; Fig. 14 is a perspective view of one of the seats for the shoe pressure limiting spring; Fig. 15 is an end view of the shoe, the control lever being broken away to show the connection between the control lever and the shoe supporting arm; and Fig. 16 is a view similar to Fig. 15, the shoe being shown in the position furthest from the roll.

Referring to the drawings, the ironer comprises a frame or casing 1 on which is supported a roll 2, a shoe 3, and the mechanism for driving the roll and for moving the shoe toward and away from the roll. At the lower end of the casing is a hollow pedestal 4 which rests on the top 5 of a suitable table and is secured thereto by screws 6 threaded from the under side of the table top into bosses 7 on the inner walls of the pedestal.

Projecting through an opening 8 in the table top into the pedestal 4 of the casing is an electric motor 9 which is resiliently supported by rubber rings 10 on a plate 11 fixed to bosses 12. The motor shaft 13 is connected by a flexible coupling 14 to a worm shaft 15 journaled in bearings 16 and 17. The bearing 16 is carried

on a boss 18 on the bottom wall 19 of the casing. The bearing 17, a combined sleeve and thrust bearing which takes the worm thrust, is carried on a boss 20 on the top wall 21 of the casing. A worm 22, cut on the shaft 15, meshes with a worm wheel 23 fixed on a shaft 24 journaled in a boss 25 in the end wall 26 of the casing. The shaft 24 is continuously driven by the motor. The boss 25 provides spaced bearings for the shaft 24 and a lubricant containing space 27 between the bearings. The shaft 24 projects outside the casing wall 26 and has a pinion 28 fixed on the projecting end thereof. The other end of the casing is closed by a removable cover plate 29.

The roll (Fig. 5) is of the construction shown in my application, Serial No. 64,480, filed February 18, 1936. It comprises a sheet metal cylinder 30 the outer surface of which is covered by a pad 31 held in place by a pad cover 32. The pad cover is held in place by snap rings 33 which fit in grooves 34 in the inner surface of the cylinder within each end. Within the ends of the cylinder are disks 35 and 36 having outwardly extending flanges 37 and 38 respectively fixed to the inner surface of the cylinder. At the center of the disks 35 and 36 are sleeves 39 and 40 having outwardly extending flanges 41 and 42 respectively secured to the disks 35 and 36 and having sleeve bearings 43 and 44 respectively fixed therein. The sleeve bearings 43 and 44 bear respectively on collars 45 and 46 which loosely surround a tube 47 fixed in a boss 48 in the end wall 26 of the ironer casing. The collars 45 and 46 are non-rotatably supported on the tube 47 in the manner shown at the right-hand end of the roll in Fig. 5. Within the tube 47 are cup-shaped seats 49 and 50 having tubular shanks 51 and 52 extending respectively into diametrically opposite openings in the walls of the tube arranged on a center line connecting the roll and shoe when the shoe is pressed against the roll. The shank 51 is slidable in its opening and the shank 52 is fixed in its opening. Extending through the tubular shanks 51 and 52 are pins 53 the upper ends of which fit in seats 54 in the inner surfaces of the collars 45 and 46 and the lower ends of which extend through openings 55 in the collars and terminate slightly within the outer surfaces thereof. Between the seats 49 and 50 and around the pins 53 are helical compression springs 56 which are strong enough to normally bias the collars 45 and 46 upward so that the lower parts; i. e., the parts shown resting against the tube 47 in

Fig. 5, are normally held against the tube. The pressure from the springs 56 is transmitted to the collars 45 and 46 through the shanks 51 and the seats 54. The supporting arrangement for the collar 45 is identical with the support for the collar 46.

When the shoe is away from the roll the collars 45 and 46 will be urged against the under side of the tube 47 and the roll will occupy the position shown in Fig. 5. In this position an internal gear 57 which is fixed to the flange 38, for example, by screws 58 threaded into the gear from the outside of the cylinder 30, will be out of mesh with the pinion 28 fixed to the continuously driven shaft 24 (Fig. 6). When the shoe is pressed against the roll the pressure of the shoe on the roll overcomes the relatively weak springs 56 and moves the roll transversely with respect to the tube 47 to the position shown in dotted lines in Fig. 10. In this position the internal gear 57 meshes with the pinion 28 completing a driving connection to the roll. Since the springs 56 are relatively weak, rotation of the roll is started before full ironing pressure is developed between the roll and the shoe. This decreases the starting load on the roll.

As the internal gear is moved into mesh with the pinion, there is a possibility of the clashing of the gear teeth which is increased by the fact that the pinion 28 is an external gear with its teeth extending radially outward and the gear 57 is an internal gear with its teeth extending radially inward. It is therefore possible for a pair of teeth on the pinion to straddle a pair of teeth on the internal gear. Under this condition, further approach of the gear teeth would cause serious jamming. This tendency for clashing or jamming of the gear teeth is prevented by the yieldable mounting for the roll provided by the collars 45 and 46 and the associated parts. As the internal gear is moved into mesh with the pinion, if the teeth are in a position to cause jamming, the right-hand end of the roll as viewed in Fig. 5, will pause in its movement while the left-hand end will continue its movement. During the pause in the movement in the right-hand end of the roll, the teeth of the continuously rotating pinion will move to a position in which the teeth may mesh without jamming.

Under some circumstances, it is desirable that the roll remain stationary when the shoe is pressed against the roll. This is accomplished by moving a block 59 between the collar 46 and the upper side of the tube 47 when the shoe is away from the roll. Under this condition, the collar will be held spaced from the upper side of the tube 47 thereby preventing movement of the internal gear 57 into mesh with the pinion 28 when the shoe is pressed against the roll. The block 59 is carried on a slide 60 which extends between the tube 47 and the collar 45 to the outer end of the roll. A handle 61 is provided on the outer end of the slide. The slide is provided with a slot 62 through which the tubular shank 51 associated with the collar 45 projects and with a slot 63 through which extends a screw 64. The head of the screw 64 overlaps the sides of the slot 63 preventing displacement of the slide around the tube. Lengthwise movement of the roll off the end of the tube 47 is prevented by a thrust washer 65 held in place by a cotter pin 66.

The shoe (Fig. 9) comprises an arcuate metal plate 67 having its rear side enclosed by a cover 68. It is heated by suitable electrical elements

(not shown) arranged between the cover and the rear side of the shoe.

The shoe is moved toward and away from the roll by a rock shaft 69 journaled in bosses 70 and 71 in the ironer casing and extending therefrom along the roll. The projecting end of the rock shaft has a reduced portion 69a journaled in the flanges 72a and 72b of a channel-shaped support 73 fixed to the table top 5. The support 73 is constructed so that it can be flexed by the deflection of the shaft 69 under the shoe pressure without disturbing the table top. The flanges 72a and 72b are held between a shoulder 69b and a snap ring 69c on the rock shaft (see Figs. 11 and 12). The shoe is supported on the rock shaft and is moved thereby into and out of engagement with the roll by a toggle which comprises an arm 74 fixed to the shoe and an arm 75 pivoted on the reduced end 69a of the rock shaft. The arm 74 has spaced walls 76 extending along the outside of the spaced outer walls 77 of the arm 75. Fixed between the walls 76 is a pivot pin 78 which extends through elongated slots 79 in the walls 77. The pin 78 is normally held at the outer ends of the slots 79 by a compression coil spring 80 arranged between a seat 81 having ears 82 slidably carried in the slots 79 and between a seat 83 of the same construction as the seat 81 fixed between walls 77 of the arm 75 adjacent the rock shaft 69 by having its ears 83a fit in openings 83b. When the arm 75 is pivoted in a counterclockwise direction, as viewed in Fig. 9, the shoe is moved against the roll. When the shoe is against the roll, as shown in Fig. 10, the pin 78 and the arms 74 and 75 lie substantially on a center line connecting the roll and the rock shaft. In this position the toggle is straightened and the full ironing pressure is developed. The ironing pressure is limited by the strength of the coil spring 80 which decreases the variation in ironing pressure with variations in the thickness of the pad 31 and of the material being ironed. When the shoe is pressed against the roll the roll rotates in the direction of the arrow 84 (Fig. 10). As explained above, the rotation of the roll starts before the development of the full ironing pressure. The friction exerted on the shoe by the roll tends to move the shoe in the direction of the arrow 84. This force, therefore, tends to move the toggle to the straightened position and assists in pressing the shoe against the roll.

The arm 75, as shown in Fig. 12, is arranged between the flanges 72a and 72b of the support 73 and the side walls 77 thereof are pivoted on the reduced portion 69a of the rock shaft 69. Slidably and rotatably carried on the rock shaft 69 is a hub 85 having notches 86a and 86b for receiving a set screw 87 threaded into the rock shaft. The hub 85 is connected to the arm 75 by a rod 88 slidably extending through the walls 77 of the bracket and having its inner end threaded into the hub 85. The outer end of the rod 88 is provided with a knob 89. Upon pushing the knob 89 to the right, as viewed in Fig. 12, the hub 85 will be moved to the right to a position in which the notches 86a and 86b are clear of the set screw 87. In this position the arm 75 can be freely pivoted on the rock shaft between the limits defined by the engagement of the set screw 87 with the walls 90 on the hub 85. For pivoting the arm 75 there is provided a channel-shaped lever 91 having flanges 92 and 93 enclosing and bearing against the ends of the hub 85 (Figs. 11 and 12). The flange 92 is pivoted on the rock shaft 69. The flange 93 is pivoted on a boss 94

on the hub 85. The flange 93 has an elongated slot 95 through which the rod 88 extends. The slot provides a lost motion connection between the lever 91 and the arm 75, permitting the lever 91 to remain stationary during oscillation of the arm 75 by the rock shaft 69. The hub 85 and the lever 91 are held in the position shown in Fig. 12 by a coil spring 96 arranged around the rod 88 and between a washer 97 fixed on the rod and the inner surface of the wall 11 adjacent to the hub 85. In this position the flange 93 of the lever 91 is held against the outer surface of the flange 72a on the support 13 and movement of the lever 91 in a clockwise direction, as viewed in Fig. 9, is limited by a stop 98 pressed out of the flange 72a which cooperates with a tongue 99 on the flange 93. When the knob 89 is moved to the right, as viewed in Fig. 12, the tongue 99 is moved clear of the stop 98 and the lever 91 may be pivoted in a clockwise direction. This movement, through the pin and slot connection provided by the slot 95 and the rod 88, will cause the arm 75 to be pivoted in a clockwise direction. This movement of the arm 75 can be used to move the shoe away from the roll independently of the rock shaft. It, therefore, serves as an emergency release to relieve the pressure between the roll and the shoe in case of failure of the power supply. It may also be used to move the shoe a greater distance from the roll, as shown in Fig. 16, to permit cleaning and waxing of the shoe. Under normal conditions the set screw 87 rests in notch 86a, in which case the shoe 3 is moved by oscillation of the rock shaft between the positions shown in Figs. 9 and 10. When the set screw rests in notch 86b, the shoe is moved by oscillation of the rock shaft between the positions shown in Figs. 15 and 16. In the position of Figs. 9 and 15, the lower edge of the shoe rests against a stop 98a on the support 13. The slot 95 and rod 88 provide a lost motion connection between the lever 91 and the arm 75 so that the lever 91 remains stationary during the oscillation of the rock shaft so long as the tongue 99 of the lever is adjacent the stop 98.

The rock shaft 69 is oscillated to move the shoe toward and away from the roll by means of a connecting rod 100 having one end pivoted on a pin 101 fixed in a crank arm 102 fixed to the rock shaft and having the other end pivoted on a pin 103 threaded into a boss 104 on a clutch member 105 loose on the continuously rotating shaft 24. The clutch member 105 has diametrically opposite grooves 106 in which are slidably carried clutch keys 107 (see Figs. 7, 8 and 3). The clutch keys are urged outward by coil springs 108 (Fig. 3) arranged between the bottom walls of the grooves 106 and tongues 109 on the clutch keys. Outward movement of the clutch keys is limited by engagement of the tongues 109 with flanges 110 at the top of the grooves 106. The clutch keys 107 are held in their inner positions by trip members 111 and 112. The trip member 111 is pivoted on a pin 113 (see Fig. 2) fixed on the ironer casing and is urged into engagement with the clutch key by a spring 114 having one end fixed in a slot 115 in the pin 113 and having the other end engaging the upper side of the trip member 111. The trip member has an outwardly extending flange 116 (Fig. 3) which engages the upper clutch key 107 and has an edge portion 117 which fits in a groove 118 in the clutch member 105. The bottom of the groove 118, as shown in Fig. 2, has an abrupt increase in depth at di-

metically opposite points providing shoulders 119 which permit the trip member 111 to move suddenly inward. At these positions the energy stored in the spring 104 causes the upper key 107 to be moved forcibly inward. The shoulders 119 also prevent clockwise movement of the clutch member, as viewed in Fig. 2. The trip member 112 is pivoted on a pin 120 pivoted on the flange 121 of a bracket 122 fixed to bosses 123. The trip member 112 is moved by a rod 124 pivoted at one end in an ear 125 on the trip member and at the other end in an arm 126 of a bell crank lever 127 pivoted at 128 on a post 128a (Fig. 5) on the gear casing. The bell crank lever 127 is urged to the position shown in Fig. 2 by a coil tension spring 129. The other arm 130 of the bell crank lever 127 cooperates with a crank 131 on the offset end of a shaft 132 journaled in a bearing 132a in the wall 26 of the ironer casing and in the support 73. Endwise movement of the shaft 132 is prevented by a snap ring 132b and a washer 132c. The shaft 132 extends along the under side of the rock shaft 69. Adjacent the support 73 is a crank 133 fixed to the shaft 132 by a set screw 134 (Fig. 9). The crank 133 cooperates with the tongue 98 on the control lever 91. When the control lever 91 is moved in a counterclockwise direction, as viewed in Fig. 9, the tongue 98 presses against the crank 133 and moves the shaft 132 in a counterclockwise direction as viewed in Figs. 2 and 9. For convenience in moving the control lever 91 the outer end has fixed thereto a rod 135 which extends along and above the front edge of the shoe as is clearly shown in Figs. 1 and 9. The rod 135 also serves as a guard for the shoe preventing burning of the operator. The counterclockwise movement of the shaft 132 causes the crank 131 to press against the arm 130 of the bell crank lever 127 pivoting the bell crank lever in a clockwise direction, as viewed in Fig. 2. This causes the rod 124 to move the trip member 112 in a clockwise direction, as viewed in Fig. 4, moving the trip member clear of the adjacent clutch key 107. The clutch key is then moved outward by the spring 108 into one of the notches 136 in the worm wheel 23 completing a driving connection from the worm wheel to the clutch member. This clutch key will be hereafter termed the driving key. The worm wheel is provided with an odd number of notches so that the other clutch key 107 is held in its inner position by the tooth 137 which is diametrically opposite the slot 136 in which the driving clutch key fits. As soon as the driving clutch key moves into one of the notches 136 the control lever 91 may be released and the trip member 112 will be returned to the position shown in Fig. 4 by the coil spring 129. Upon rotation of the clutch member through 180 degrees the trip member 111 forcibly moves the driving clutch key out of engagement with the notch 136. The disengaging movement of the driving clutch key is made more positive by the moving of the edge 117 of the trip member 111 off the abrupt shoulder 119 which releases the energy stored in the spring 104. The driving clutch key, therefore, is moved positively inward clear of the teeth 137 breaking the driving connection to the clutch member 105. The other clutch key is held in the inner position by the trip member 112 which has returned to the position shown in Fig. 4.

By this arrangement it is apparent the successive actuations of the control lever 81 will cause the clutch member 105 to be moved in 180

degree steps. When the clutch member 105 is in the position shown in Fig. 2 the shoe is separated from the roll. The parts are held in this position by a tension spring 138 arranged between the gear casing and the pivot pin 103 which tends to turn the clutch member in a counterclockwise direction, as viewed in Fig. 2, holding the shoulder 119 against the edge 117 of the trip member 111 and preventing overtravel of the clutch member. When the clutch member 105 has been turned 180 degrees from the position shown in Fig. 2, the shoe will be pressed against the roll. In this position the rotation of the roll exerts a frictional force tending to rotate the shaft 69 in a counterclockwise direction, as viewed in Fig. 2, exerting a pull on the clutch which prevents overtravel. An additional force tending to prevent overtravel is obtained from the shoe supporting toggle 74, 75 due to the fact that the pin 78 is displaced from the center line of the toggle links when the shoe is in the closed position. This is the sole force present when the roll is stationary. When the shoe is in the closed position, the force of the spring 138 acts in a direction to cause overtravel of the clutch. It is, however, too weak to cause overtravel. The weight of the shoe is balanced by a spring 139 arranged between the gear casing and the pivot pin 101. This eliminates unbalanced weight acting on the mechanism which might prevent smooth action.

In the use of the ironer, the material to be ironed is arranged on the roll while the shoe is separated from the roll. A momentary downward pressure is then exerted on the control lever 91 through the rod 135 causing the trip member 112 to be moved clear of the adjacent clutch key 107 and permitting the adjacent clutch key 107 to be moved outward into one of the notches 136 in the worm wheel 23 establishing a driving connection to the clutch member 105. This driving connection is broken at the end of a 180 degree rotation of the clutch member by the trip member 111 which forcibly moves the clutch key inward clear of the notch 136. The 180 degree rotation of the clutch member 105 causes the shoe to be pressed against the roll and by the pressure exerted on the roll by the shoe causes the internal gear 57 to be moved into engagement with the pinion 28 starting the rotation of the roll.

At the completion of the ironing the shoe is moved away from the roll by pressing downward on the rod 135 initiating another 180 degree rotation of the clutch member 105 which returns the parts to the position shown in Fig. 2.

If it is desired that the roll remain stationary when the shoe is pressed against the roll, the slide 60 is pushed inward moving the block 59 between the tube 47 and the inner surface of the collar 46. This holds the internal gear 57 clear of the pinion 28 so that the driving connection to the roll is not established.

In an emergency the shoe may be moved away from the roll by the control lever 91. This is accomplished by pushing the knob 89 to the right, as viewed in Fig. 12, thereby moving the hub 85 to a position in which the notch 86a is clear of the set screw 87. This breaks the connection between the hub 85 and the rock shaft 69. By pivoting the control lever 91 in a clockwise direction, as viewed in Fig. 9, the shoe supporting arm 75 may be pivoted in a clockwise direction to move the shoe away from the roll. The connection between the arm 75 and the control lever 91 comprises the rod 88 and the slot 95. When the shoe is separated from the roll the hub 85 is pivoted to a position in which the set screw 87 fits in the notch 86b. The position of the parts under this condition is shown in Fig. 15. If the rock shaft is rotated to the position shown in Fig. 16, which rotation may be effected by exerting a momentary downward pressure on the rod 135, the parts will be moved to the position shown in Fig. 16 in which the shoe is further separated from the roll. In this position the shoe may be cleaned and waxed.

25. What I claim as new and desire to secure by Letters Patent of the United States, is:

1. In an ironer, a roll, a shoe, power driven mechanism for effecting engagement and separation of the roll and shoe, manually operable mechanism for effecting release of the pressure between the roll and shoe, a control lever for said power driven mechanism extending over the shoe, and independently operable connections between the control lever and the release and power driven mechanisms whereby the release mechanism may be operated by the control lever independent of said power driven mechanism.

2. In an ironer, a roll, a shoe, power driven mechanism for effecting engagement and separation of the roll and shoe, manually operable mechanism for effecting release of the pressure between the roll and shoe, a control lever extending over the shoe, and independently operable connections between the control lever and said power driven and release mechanisms whereby said mechanisms may be selectively operated by said lever.

3. In an ironer, a roll, a shoe, a rock shaft, an arm on the rock shaft connected to the shoe whereby the shoe is moved toward and away from the roll upon oscillation of the rock shaft, power driven mechanism for driving the roll and for oscillating the rock shaft, a control lever for said mechanism extending from the rock shaft over the shoe, and selectively operable connections between said lever and said arm whereby said arm may be moved by said lever relative to the roll independent of said mechanism.

GEORGE W. WARDWELL, JR.
